CUSHION SHANK FOR SHOES

William H. Nickerson, Newton Center, Mass.

Application August 3, 1935, Serial No. 34,542

2 Claims. (Cl. 36—76)

The present invention relates to shank cushions adapted to be incorporated in shoes for supporting the arch of the wearer's foot and otherwise enhancing the comfort of the shoe. It comprises 5 essentially a cushion which may be embodied in a variety of forms and combined with a shoe shank stiffener in various ways, and further comprises the combination of such cushion and stiffener with one another and with a shoe.

10 In the drawing furnished herewith,—

Figure 1 is a perspective view, partly broken away and shown in section, of one form of shank cushion and arch support embodying this invention.

15 Figure 2 is a perspective view of a steel shank stiffener in connection with which said cushion may be used.

Figure 3 is a longitudinal sectional view of the cushion shown in Figure 1 and the shank stiffener 20 shown in Figure 2 assembled with one another in the manner in which they are incorporated in a shoe.

Figure 4 is a detail section taken transversely through the forward end of the assembled cushion 25 and stiffener taken on line 4—4 of Figure 3.

Figures 5 and 6 are views similar to Figure 4 showing variations in the form of the forward abutment between the cushion and the stiffener.

Figure 7 is a perspective view of an alternative 30 form of shank cushion embodying the invention.

Figure 8 is a fragmentary longitudinal section through the shank part of a shoe showing the cushion of Figure 7 combined with a steel shank stiffener between the inner and outer soles of a shoe.

35 Figure 9 is a cross section of the combined cushion and shank stiffener shown in Figure 3, taken on line 9—9 of that figure.

Figure 10 is a similar cross section of the cushion shown in Figure 7 and a shank stiffener in their assembled relationship prior to being confined between the inner and outer soles of a shoe.

Figure 11 is a perspective view, partly broken away and shown in section, of a shank cushion 45 like that shown in Figure 1 but having the specific design shown in Figure 5.

Like reference characters designate the same parts wherever they occur in all the figures.

50 The cushion members here shown are of flexible and more or less compressible and resilient material. Preferably they are made of a good quality of vulcanized rubber having sufficient resilience to give the desired cushioning effect. The properties 55 of the rubber composition may be varied to such

extent as needed to make the cushion firmer or more yielding to meet different requirements.

The cushion shown in Figure 1 is formed to co-operate with a metal shank stiffener of the design shown in Figure 2; such shank stiffener being 5 preferably made of stiff sheet steel pressed or molded with a longitudinally arched formation conformable to the longitudinal arch of the human foot, and also being transversely arched to increase its stiffness. This stiffener is designated 10 as a whole by the reference letter *a*. Its forward end *a*¹ is intended to terminate at the ball of the shoe for which it is designed, and its rear end to extend beyond the breast of the heel. The relationship of its longitudinal and transverse curvatures is such that the concave side of the transverse curvature is directed toward the inner sole when it is placed in a shoe.

The cushion *b* in Figure 1 has a flat upper face 20 to bear against the outer surface of the inner sole, and it contains a convex rib *c* at the opposite side which substantially conforms to the hollow transverse curvature of the stiffener, as represented by Figure 9. It is formed with flanges *d*, *d* at the sides which overlap the side edges of the stiffener. 25 It is longer than the stiffener and wider at both ends, and contains at its rear end a pocket *e* adapted to receive the rear end *a*² of the stiffener, and at its forward end a pocket or recess *f* to receive the forward end *a*¹ of the stiffener. The 30 pocket *e* has an open mouth facing forwardly, but otherwise is closed. The pocket or recess *f* faces to the rear and has a sufficient width of opening to receive the end *a*¹ of the stiffener, which is its widest end. The flexibility and resilience of the 35 cushion permit it to be bent and stretched sufficiently to receive the opposite ends of the stiffener in its pockets, and cause it thereafter to confine the stiffener so that accidental disassociation of the cushion and stiffener is practically impossible. 40

The forward end of the cushion is tapered nearly to a thin edge. That is, it is reduced in thickness so that it does not cause any appreciable ridge in either the inner or outer sole at its termination slightly forward of the ball of the shoe.

45 The forward end of the stiffener may have any one of various outlines and the abutting limit of the pocket *f* is preferably made to correspond. Thus, Figures 2 and 4 show a concave curvature in the forward edge *a*³ of the stiffener and a complementary convexity *g* at the inner limit of the pocket. Figure 5 shows the corresponding abutting edges *a*⁴ and *g*' of the stiffener and cushion as being straight; and Figure 11 shows by dotted lines this formation of the pocket. Figure 6 50 55

shows a convexity a^5 in the forward end of the stiffener and a concavity g^2 in the complementary abutment of the cushion.

An optional feature of the cushion is a pad h at the upper side near its forward end; such pad being suitably located and of suitable thickness and contour to serve as a support for the metatarsal arch of the foot. If desired, in order to enhance the flexibility and resilience of this pad, the under side of the cushion may be so molded as to leave a space i between the pad and the underlying part of the stiffener a . But this is not essential and the cushion may be made solid throughout from the outer surface of the pad to the stiffener. In the latter case a firmer and less yielding support is given to the metatarsal arch.

The cushion j shown in Figures 7, 8, and 10, is adapted to lie beneath the stiffener and between the latter and the outer sole. It has pockets e^1 and f^1 at its ends for the stiffener, which are similar to the pockets e and f , respectively, except that they open on the upper side instead of the under side of the cushion. The intermediate part of this cushion is shown as being substantially flat and of uniform thickness in cross section. In the shaping of the outer sole to give the usual convex formation to the shank part thereof, the cushion is bent and then conforms at its upper side to the curvature of the stiffener.

In the shoe the cushion extends longitudinally to substantially the extent shown in Figure 8, its rear end passing well over the heel and providing a heel cushion, while its forward end extends to, or across, the ball of the shoe. Although Figure 8 represents the form of cushion with reference to Figures 7 and 10 described, it will be understood that the one shown in Figures 1 and 3 is similarly placed (except that it is between the stiffener and the inner sole) and extends to substantially or nearly the same points at its opposite ends.

Shank stiffeners are also used in which the transverse concavity is turned toward the outer sole, exactly opposite to the formation shown in Figures 2, 9, and 10. I contemplate making the cushion of either type here shown conformable to such shanks of reversed curvature. In fact, the cushions may be molded with any desired cross sectional shape or width, whether to fit or bridge across the concavity of the transversely arched stiffener or to conform with the convex side of such a stiffener, or with the flat faces of stiffeners which have no transverse arch.

A feature common to all embodiments of the invention is the pockets at front and rear ends

for the corresponding ends of the stiffeners. The term "pockets" here used comprehends not only the recesses which embrace the opposite edges of the intruding end of the stiffener, but also such recesses as that shown in f , which are open at both sides and do not embrace the edges of the stiffener. It should be noted that notwithstanding the open sided formation thus shown of the pocket f , there is an interlock with the adjacent end of the stiffener, caused either by the concave or by the convex formations of Figures 2, 4 and 6, or the substantial width of the straight abutting edges shown in Figure 5. The stiffener is so well anchored by these pockets and by the frictional and compressed gripping of the cushion between the inner and outer soles, that it cannot get out of place in the shoe, and needs no extraneous holding means such as the tacks or prongs commonly used with shank stiffeners when there is no cushion. This security is obtained without a permanent union between the metal shank and the cushion, such as might be effected by molding the cushion around the stiffener, or some part of it, or vulcanizing them together. Instead, a series of cushions comprising any desired number of different sizes and designs may be assembled when needed, each with any one of several different metallic shank stiffeners.

What I claim and desire to secure by Letters Patent is:

1. The combination with a shank stiffener having longitudinal and transverse curvature of a cushion adapted to overlie such stiffener, having a rib on one side to fit the concavity of the stiffener and having pockets opening from the same side near the opposite ends and extending respectively toward such ends, adapted to receive the corresponding ends of the stiffener.

2. The combination with a metallic shoe shank stiffener of a flexible elastic and resilient shoe shank cushion having a length greater than that of the stiffener and having pockets opening from one side near the opposite ends, each pocket extending toward the respectively nearer end, the mouths of such pockets being separated from one another by a distance less than the length of the stiffener, and the bottoms of the pockets being a distance apart substantially equal to the length of the stiffener, whereby the stiffener is insertible into both pockets after stretching of the cushion and is retained by the resilient contraction of the cushion.

WILLIAM H. NICKERSON.
